UNITED STATES PATENT OFFICE.

JOHN MCINTYRE, OF JERSEY CITY, NEW JERSEY.

ELECTROMAGNETIC APPARATUS.

1,029,388.

Specification of Letters Patent. Patented June 11, 1912.

Application filed May 29, 1906. Serial No. 319,260.

To all whom it may concern:

Be it known that I, JOHN MCINTYRE, a citizen of the United States, and a resident of Jersey City, in the county of Hudson 5 and State of New Jersey, have invented a new and Improved Electromagnetic Apparatus, of which the following is a full, clear, and exact description.

The invention relates to Ruhmkorff coils 10 and similar apparatus, and its object is to provide a new and improved electromagnetic apparatus arranged to increase the speed and force of the vibratory armature, and to insure an uninterrupted response of 15 the armature for a long period without the danger of the armature sticking at the contacts.

The invention consists of novel features 20 and parts and combinations of the same, which will be more fully described herein-after and then pointed out in the claims.

A practical embodiment of the invention 25 is represented in the accompanying drawing forming a part of this specification, in which similar characters of reference indicate corresponding parts in all the views.

Figure 1 is a plan view of the improvement; Fig. 2 is a like view of a modified form of the improvement; Fig. 3 is an end 30 elevation of the same, the fixed contact being omitted.

On the base A of the electromagnetic apparatus is mounted the usual electromagnet B carrying the primary and secondary 35 wires and the central core C, opposite the outer end of which is arranged the armature D' held on the free end of a spring armature lever D fixed at its other end in a suitable post E carried by the base 40 A. Although I have shown a spring armature lever D it is evident that any other form of vibratory armature may be employed. On the armature lever D between the armature D' and the fixed end is held 45 a contact D² opposite a contact F' secured or formed on one end of a bar F adjustably secured in a post G attached to the base A. On the base A is mounted a magnet H which 50 may be in the form of a permanent magnet or in the shape of an electromagnet by having a wire H' coiled around a piece of iron and connected with a suitable source of electrical energy, such as a battery or the like. 55 The pole H² of the magnet H is in close proximity to but spaced from the armature

D', to permit of an exchange of energy through the space between the armature and the said magnet. In order to obtain the most efficient result I prefer to arrange the pole H² in such a manner that the line or path of the energy is approximately at right angles to the movement of the armature D'. The magnet H is wholly separate from the armature D' and its lever D, and is adjustable on the base A to permit of bringing the pole H² as close as possible to the armature D', without however touching the latter and impeding its vibratory motion. For the purpose mentioned the magnet H is provided with a flange H³ having an elongated aperture H⁴ engaged by a screw J screwing into the base A, so that on loosening the screw J the magnet can be adjusted to bring the point H² into the desired relation to the armature D'. When this has been done the screw J is screwed up to secure the magnet H in position on the base A. In the arrangement shown in Fig. 2, a piece of iron H⁵ extends at right angles to the core C, and its delivery point H⁶ is in close proximity to the armature D' without touching it. In this case the piece of iron receives induced magnetism from the core C of the electromagnet by a path approximately at right angles to the travel of the vibratory armature D'. The piece of iron H⁵ may abut against a permanent magnet H⁷ to derive magnetism from the said permanent magnet H⁷. Now, the piece of iron H⁵ as well as the permanent magnet H⁷ are provided with slotted flanges H⁸, H⁹ engaged by screws J', J² for securing the piece of iron H⁵ and the permanent magnet H⁷ in position after the same has been adjusted, to bring the piece of iron H⁵ in proper relation to the armature D', and to abut the permanent magnet H⁷ on the piece of iron H⁶.

By the arrangement described, the magnets H, H¹⁰ or the piece of iron H⁵ and its permanent magnet H⁷, each form a supplementary means for increasing the energy of the core C of the electromagnet B by way of the armature D' so that the latter is more forcibly attracted when the electromagnet B is energized, and when the electromagnet B is deenergized then the armature D' and its lever D return to normal position by the inherent and unimpeded resiliency of the armature lever. By the arrangement described, the movement of the armature D' 110

toward the core C is increased both in speed and force, and an increase in speed and force is had for the return movement of the armature, and, consequently, the vibratory armature is not liable to stick at the contacts D², F', and an uninterrupted response of the armature is had for a long period.

It is understood that in either of the forms shown and described the armature is the medium for the transmission of the magnetic energy between the core C and the supplementary means, and as the latter is not in contact with the vibratory portion of the armature and is located outside of the path of movement of the armature, it is evident that the said supplementary means do not impede or retard the vibratory motion of the armature, and hence a proper response thereof relative to the action of the core and a forceful return movement of the armature, is insured. It is understood that the action of the supplementary means referred to increases or diminishes according to its own force, that is, if stronger magnets are used the force of the supplementary means is increased, and reversedly decreased on diminishing the force of the supplementary means.

It is understood that the apparatus is provided with the usual binding posts and wire connections, and further description is not deemed necessary.

Having thus described my invention, I

claim as new and desire to secure by Letters Patent:

1. An electromagnetic apparatus of the 35 class described comprising a main electromagnet having a straight core, an auxiliary magnet disposed in the field of said main magnet so as to augment the same, an armature for said main magnet arranged to move 40 toward and away from the pole of said main magnet, said auxiliary magnet being adapted to project a field against the armature at right angles to its line of movement.

2. An electromagnetic apparatus of the 45 class described comprising a main electromagnet having a straight core, an auxiliary magnet disposed in the field of said main electromagnet so as to augment the same, an armature disposed near one pole of said 50 main magnet and arranged to move toward and away therefrom in a direction parallel with the axis of the main magnet, one pole of said auxiliary magnet being bent into close proximity to said armature, and being adapted 55 to project a field against the armature at right angles to its line of movement.

In testimony whereof I have signed my name to this specification in the presence of two subscribing witnesses.

JOHN McINTYRE.
